BROILER REFLECTOR OR THE LIKE

Richard D. Reagan, Addison, N.Y., assignor to Corning
Glass Works, Corning, N.Y.

Filed Jan. 28, 1971, Ser. No. 110,793

Term of patent 14 years

Int. Cl. D7—99

U.S. Cl. D81—10

Fig. 1

Fig. 2

Fig. 3

Fig. 4

Fig. 5

FIG. 1 is a bottom plan view of a broiler reflector or the like embodying my new design.

FIG. 2 is an end elevational view as viewed from the lower side of FIG. 1.

FIG. 3 is a side elevational view as viewed along line 3—3 of FIG. 1.

FIG. 4 is a top plan view as viewed along line 4—4 of FIG. 2.

FIG. 5 is an end elevational view as viewed along the top of FIG. 1 and along line 5—5 of FIG. 3.

I claim:

The ornamental design for a broiler reflector or the like, as shown.
